UNITED STATES PATENT OFFICE.

ELI J. MANVILLE, OF WATERBURY, CONNECTICUT.

MACHINE FOR TAPPING GAS AND WATER FITTINGS.

SPECIFICATION forming part of Letters Patent No. 308,182, dated November 18, 1884.

Application filed December 31, 1883. (No model.)

To all whom it may concern:

Be it known that I, ELI J. MANVILLE, of Waterbury, in the county of New Haven and State of Connecticut, have invented a new Improvement in Taps for Steam and Gas Fittings; and I do hereby declare the following, when taken in connection with accompanying drawings and the letters of reference marked thereon, to be a full, clear, and exact description of the same, and which said drawings constitute part of this specification, and represent, in—
Figure 1, a top or plan view; Fig. 2, a transverse section on line $x-x$, looking forward; Fig. 3, a side view of the mandrel and the tap mechanism; Fig. 4, a side view showing a portion of the sleeve L cut away; Fig. 5, a longitudinal central section; Fig. 6, a front end view with the covering-plate removed, showing the dies in their thrown-out or projecting position; Fig. 7, the same figure, showing the dies in their drawn or contracted position; Fig. 8, a section on line $y-y$ of Fig. 5, looking rearward, and showing the parts as when the dies are thrown out into active position; Fig. 9, the same section, showing the dies drawn inward or into the contracted position; Fig. 10, a transverse section on line $z-z$; Figs. 3 to 10, inclusive, enlarged.

This invention relates to an improvement in machines for tapping gas and water fittings, with special reference to the revolving tap which is advanced toward the thing to be tapped and withdrawn after the thread is cut, the object being the construction of a tap in which the cutting-dies shall be readily movable, and so that such movable dies shall be automatically thrown outward and held as the tap approaches the thing to be tapped, and after the thread has been cut the said dies will be automatically drawn inward to permit the die to be removed without reversing its rotation; and the invention consists, principally, in screw-cutting dies arranged radially in a revolving head combined with a cam centrally between said dies, to which cam partial rotation is imparted before the screw-cutting dies commence their operation, and such rotation of the cam operating to force the dies radially outward into working position, and to hold them in that position until the screw-cutting is accomplished, and then a rotation imparted to the cam in the opposite direction will release the

dies and permit them to recede radially away from the thread which they have cut, and so that the tap may be withdrawn without reversing this revolution, as more fully herein-after described.

In illustrating the machine I show only that part which carries the tap. The devices for holding the article to be tapped being immaterial to this invention, I have not included them in the drawings.

A represents the bed of the machine, on which, in suitable bearings, B B, an arbor, C, is arranged, free to rotate in the bearings, and also free for axial or longitudinal movement. Between the bearings, and on the arbor, a pulley, D, is arranged in engagement with the arbor, so as to impart rotation to it, but held to prevent its longitudinal movement, the connection between the arbor and pulley being the usual spline-and-groove arrangement, too well known to require particular description in this specification. Longitudinal movement is imparted to the arbor by connection with an annular groove, a, at its rear end, or otherwise, also a well known device, and not necessary to be described in this specification, as my invention relates only to the tap. The tap consists of a mandrel, E, which is introduced into the forward end of the arbor C in the usual manner of introducing other tools into such a revolving arbor. Concentrically within the mandrel, and entering from its forward end, is a spindle, F, carrying at its forward end cams b, corresponding to the number of threading-dies. Between the faces of the cams b a recess, d, is formed. At the outer end of the mandrel is a head, G, in which are radial recesses to receive the thread-cutting dies g. These dies are arranged radially in the recesses, as seen in Fig. 6, and so that when the faces of the cams b stand in line with the dies, as seen in Fig. 6, the dies are forced outward to their working position, but when the cam is turned to the intermediate position, as seen in Fig. 7, to bring the recesses d into line with the dies g, then the dies g will move radially inward into such recesses, the depth of the recesses being greater than the depth of the thread which the dies are to cut. Around the mandrel, and in rear of the dies, is a sleeve, H. From this sleeve a stud or pin, e, passes through a short annular slot, f, into the spin-

dle F, which makes a firm connection between the spindle and the sleeve, and so that both the spindle and sleeve may have a rotation independent of the mandrel, or vice versa, to 5 the extent of the slot f, the pin in the slot preventing longitudinal movement of the sleeve; hence by turning the sleeve independent of the mandrel the spindle will be turned with it, say as from the position seen in Fig. 6 to that 10 in Fig. 7, or vice versa.

To force the dies inward as the cam is turned, a projection, i, is made on the rear edge of each of the dies, to extend beneath the sleeve H. The inner surface of the sleeve over these 15 projections is made cam-shaped, the reverse of the spindle, as seen in Figs. 8 and 9, and so that when the dies are out, as seen in Fig. 6, the projections i stand in a corresponding recess, l, in the sleeve, but when the sleeve and 20 spindle are turned to take the cams b from beneath the dies, as seen in Fig. 7, then the inward projections or cam-surfaces m on the sleeve bear upon the projections i of the dies and force them inward, as seen in Fig. 9.

25 In rear of the sleeve H is another sleeve, I, and over this sleeve is a second sleeve, L. Through the two sleeves a screw, M, passes into a longitudinal slot, N, in the mandrel, as seen in Fig. 4, which engages the sleeve with 30 the mandrel, so that the sleeve will revolve with it, but yet permit a certain amount of longitudinal movement to the sleeve independent of the mandrel.

In the sleeve I is a slot, n, standing at an angle of about forty-five degrees. From the spindle F a stud, r, extends outward through a short annular slot, s, in the mandrel into the diagonal slot n in the sleeve I, and so that if a partial rotation be given to the spindle independent of the mandrel, or vice versa, it 40 will, because of the inclination of the slot n in the sleeve I, impart a corresponding longitudinal movement to said sleeve I, as indicated in broken lines, Fig. 4.

45 On the rear end of the sleeve H is a shoulder, t. On the frame or bed of the machine is a hinged dog, u, which rides upon the surface of the sleeve H. (See Figs. 1 and 2.) Supposing the rotation of the mandrel and screw- 50 cutting dies to commence in the position seen in Fig. 1, where the parts are shown in their extreme rear position, the dies advance and, entering the hole to be threaded, engage therewith, and from the time of such engagement 55 the dies advance according to the pitch of the thread and take with them the mandrel and sleeves thereon, and continue to advance until the dog u will fall from the surface of the sleeve H, as seen in broken lines, Fig. 2, and 60 into the path of the shoulder t. That shoulder coming in contact with the nose of the dog will cause the sleeve H to stop, and with it the spindle F; but the dies g will continue their rotation, because of their connection with 65 the mandrel E. This movement will take the dies from the position in Fig. 6 to the position in Fig. 7 with relation to the cams, in

which movement the dies are drawn inward and out of engagement with the thread they are cutting. During the time in which the 70 sleeve is standing and the mandrel rotating, a cam, w, on the surface of the mandrel, in rear of the shoulder t, passes beneath the dog and raises the dog out of engagement with the shoulder t, as seen in broken lines, Fig. 2, and 75 so that from the time of such disengagement of the dog the sleeve H and the part connected with it are free to revolve with the mandrel. During the time the spindle F is standing as before described the stud r thereon operates 80 in connection with the diagonal slot n in the sleeve I, and so that the sleeve I, revolving with the mandrel, will, because of the inclination of the slot n, be forced to the rear, as indicated in broken lines, Fig. 4. In this condition, the dies having completed their work, the arbor C is permitted to return, taking with it the mandrel E and all in connection therewith. In such rear movement an annular flange, P, on the sleeve L strikes a stationary finger, T, before the rear movement is completed. The rear movement of the mandrel continuing while the sleeve I is thus held by the stop or finger T causes the stud r to move rearward through the diagonal slot n, 90 which movement, because of the inclination of the slot n, will impart a corresponding rotation to the spindle, and which rotation of the spindle will by means of the stud e be imparted to the sleeve H to return it—that is, to 95 the position seen in Fig. 8—leaving the dies free, and during this movement the rotation of the spindle will cause the cams b to force the dies outward and into the working position before described and as seen in Fig. 6, in 100 which position they are ready for action, as before. Thus it will be seen that the mandrel revolves continually in one direction, and that the dies act to cut the thread, and so soon as the cutting is completed they are automatically drawn inward, because of the continued 105 rotation of the mandrel, and when so drawn inward are permitted to retreat from the hole which they have tapped, and after such retreat are automatically returned into the cutting position by the same continued rotation of the mandrel, and thus I avoid the necessity of any reverse gear to withdraw the dies, and the consequent loss of time.

The sleeve L is applied as a cover for the 110 slot n in the sleeve I; but they are to be considered practically as a single sleeve.

While I prefer the dog u to arrest the rotation of the spindles, it will be readily seen that I do not wish to be understood as limiting myself to this particular device, and while I prefer the connection between the two sleeves H and I, whereby the cams will be returned through the instrumentality of the said sleeve I, I do not wish to be limited to this particular device for returning the cams.

I claim—

1. The combination of a continuously-revolving mandrel, E, the radially-moving dies

5 *g*, the spindle *F* longitudinally within said mandrel, provided with cams *b* and intermediate recesses, *d*, the sleeve *H* outside said mandrel, and in connection with the spindle 10 within the mandrel, with a stop, substantially such as described, to arrest the rotation of the sleeve and spindle at a predetermined time, whereby the cams on said spindle will be thrown from their position supporting the dies 15 and permit the inward movement of the dies, substantially as described.

15 2. The combination of the revolving mandrel *E*, the radial dies *g*, arranged thereon, the spindle *F* within said mandrel, carrying cams *b*, with intermediate recesses, *d*, the sleeve *H* on said mandrel, constructed with a shoulder, *t*, cam *w* on the mandrel, and the dog *u*, substantially as described.

20 3. The combination of the revolving mandrel *E*, the radial dies *g* thereon, said dies constructed with projections *i*, the spindle *F* in said mandrel, provided with the cams *b*, and intermediate recesses, *d*, the sleeve *H* on said mandrel, and in connection with said spindle 25 through an annular slot in said mandrel, the said sleeve constructed with cams *m* and intermediate recesses, *l*, upon its inner face and

outside the projection *i*, with the mechanism, substantially such as described, to arrest the rotation of said sleeve at a predetermined time, substantially as and for the purpose described. 30

4. The combination of the revolving mandrel *E*, the radial dies *g* thereon, the spindle *F* longitudinally in said mandrel, provided with cams *b* and intermediate recesses, *d*, the sleeve *H* on said mandrel, and in connection with said spindle through an annular slot in the mandrel, the mechanism, substantially such as described, to arrest the rotation of the sleeve at a predetermined time, the sleeve *I* on said mandrel in rear of the sleeve *H*, the said sleeve *I* engaged with the mandrel so as to ride thereon, but free for longitudinal movement independent of said mandrel, said sleeve 45 *I* constructed with a diagonal slot, *n*, into which a stud from the spindle *F* extends through an annular slot in the mandrel, substantially as and for the purpose described. 40
